UNITED STATES PATENT OFFICE.

WILLIAM D. COIL, OF MUNCIE, INDIANA.

EGG-CASE FILLER.

1,308,578.

Specification of Letters Patent.

Patented July 1, 1919.

Application filed July 27, 1917. Serial No. 183,100.

To all whom it may concern:

Be it known that I, WILLIAM D. COIL, a citizen of the United States, residing at Muncie, in the county of Delaware and State 5 of Indiana, have invented certain new and useful Improvements in Egg-Case Fillers, of which the following is a specification.

This invention relates to improvements in egg case fillers, and particularly to that type 10 of filler which is made up of series of interlocked longitudinal and cross strips of straw board, or other suitable material.

It has been the practice to allow the ends 15 of the strips to project slightly beyond the cells formed thereby so that they abut against the inner walls of the case to serve the purpose of preventing the fillers from slipping. It has been found, however, that in shipment the jolting caused by the starting 20 and stopping of the train causes the ends of these strips to bend over and thus allow the fillers to slip back and forth, resulting in breakage of the eggs.

The object of this invention is to provide 25 a construction whereby this slippage is prevented.

It should be explained that in shipping these egg cases they are all placed in the car in the same direction and it is usually the 30 ends of those strips which extend in the direction of the train which become bent so that my improvement relates to means for preventing the slippage of the fillers in a longitudinal direction which is the direction 35 of the train.

In the drawings:

Figure 1 is a perspective view of an egg case and its fillers, one side of the case and its top being removed.

40 Fig. 2 is a top plan view of an egg case and its fillers with one of the division walls between the fillers broken away with the top of the case removed.

Fig. 3 is a section on the line 3—3 of 45 Fig. 2.

Fig. 4 is a detail sectional view.

Referring to the drawings, 1 represents the bottom, 2 one of the ends, 3 the sides and 4 one of the division walls of an egg case, 50 constructed in the usual manner. In the drawings there has been shown five fillers. Each one of these fillers is constructed of a series of longitudinal strips 5 and a series of cross strips 6 interlocked in the usual way of

making these fillers, so far as the joint between them is concerned. Heretofore it has been usual to so interlock the strips that the top and bottom edges of the strips will coincide or be in the same transverse plane. In the present case, however, the top edges of 55 the cross strips 6 project above the top edges of the longitudinal strips and the longitudinal strips project below the edges of the cross strips. It is necessary to place division walls between adjacent fillers and such division walls are represented by 7. In the present case each of these division walls is so formed as to provide a series of upwardly-extending transversely-arranged ribs 8 which form in effect a series of grooves on 70 the under surface of the walls, these ribs being equal in number to the transverse strips 6 and arranged the same distance apart as such strips. It will thus be seen that when the division walls are in place the upper 75 edges of the transverse strips will fit into these grooves, and, as the division walls 7 snugly fit the interior of the case, the egg cells will all be locked from slipping in a longitudinal direction.

To accommodate the ribs 8 thus formed on the division walls, the longitudinal strips 5 are formed with notches 9 on the lower edges equal in number to the ribs of each division wall which allows the lower edges 85 of the strips 5 to rest on the apex of the grooves of the division walls. This also furnishes an additional lock for the fillers since the notches 9 are formed to snugly fit the rib, so that each filler is locked against longitudinal movement both at the top and bottom.

It will be noticed that the grooves in the ribs are of a V-form which allows the division walls to be more readily inserted in 95 place and when they are in position the projecting edges of the strips will be in the extreme apex portion of the V so that there can be little play which would afford longitudinal slippage. It will also be seen that 100 the notches 9 are of a V-form to fit the V-shape of the ribs for the same purpose.

Each of the longitudinal strips 5 also has along its top edge notches 9^a to guide the cross strips to position in assembling the 105 strips, these notches 9^a being in line with the ones 9. The upper notches 9 coöperate with the lower edges of the cross strips for

assembling purposes while the lower notches 9 coöperate with the ribs 8 of the partitions as before explained.

Having thus described my invention, I 5 claim:—

1. In a structure of the character described, a case, a plurality of fillers, each filler consisting of a series of longitudinal strips and a series of transversely arranged 10 strips with the ends of the strips abutting the interior walls of said case, one of the edges of each strip of one series projecting beyond the corresponding edges of the strips of the other series, and a series of divisional 15 walls, each divisional wall having grooved ribs to receive said projecting edges, the strips of said other series having notches to receive the ribs of an adjacent division wall.
2. In a structure of the character de- 20 scribed, a filler consisting of a series of longitudinal strips and a series of cross strips, the top edges of said cross strips being above all portions of the top edges of the other series of strips, and a transversely arranged 25 division wall between adjacent fillers having a series of grooves on one side thereof only

corresponding in number and spacing to the number and spacing of the said cross strips so as to receive the upper edges of said cross strips, for the purpose specified. 30

3. In a structure of the character de- 35 scribed, a filler consisting of a series of longitudinal strips and a series of cross strips, the top edges of said cross strips being above all portions of the top edges of the other series of strips, and a transversely arranged 40 division wall between adjacent fillers having a series of grooves corresponding in number and spacing to the number and spacing of the said cross strips so as to receive the upper edges of said cross strips, the bottom edges of the longitudinal strips being provided with notches to receive the ribs of their corresponding division wall so that 45 said edges may rest upon said wall between said ribs.

In testimony whereof I have hereunto set my hand this 21st day of July, 1917.

WILLIAM D. COIL.
